INVENTOR:
WERNER Heyd
By *Oto Munk*
his ATTORNEY.

UNITED STATES PATENT OFFICE.

WERNER HEYD, OF FREILASSING, GERMANY.

PLASTER LATHING.

Application filed June 20, 1921. Serial No. 478,871.

To all whom it may concern:

Be it known that I, WERNER HEYD, citizen of Germany, residing at Freilassing, Bavaria, Germany, have invented certain new and useful Improvements in Plaster Lathings; and I do hereby declare the following to be a full, clear, and exact description of the invention, such as will enable others skilled in the art to which it appertains to make and use the same.

This invention relates to plaster lathings, for use more particularly in making ceilings and walls.

In the ordinary plaster lathing for ceilings and walls which are made of wood-mats or wood lath structures the wood laths, which are usually rectangular in section lie with one of their sides on the wire support.

The plaster is thus merely retained by adhesion on the outer and side faces of the wood laths. In order to increase this adhesion the laths have been given a different section, for example a trapezoidal form whereby a retention of the plaster is obtained not merely by adhesion to the surfaces of the wood laths but also by obtaining a dove-tailed locking between the lath.

By forming the laths of trapezoidal section the difficulties and cost of manufacture are substantially increased.

Now this invention has for its object to obtain in similar manner a dove-tailed locking of the plaster by the laths whilst retaining the former rectangular section of the laths.

For this purpose the wood laths which are of the ordinary rectangular section are each placed with one edge on the wire foundation and woven thereto in the ordinary way. By placing the laths cornerwise on the wire foundation the plaster has offered to it, not as hitherto three faces, but all four faces of each bar in such a way that the plaster penetrates between the bars, encloses them and is thereby dovetailed between them.

By this means the plaster binding is given a larger surface of contact and more power of resistance to its being loosened, whilst by still retaining the rectangular form of the bars the manufacture is still simple and inexpensive.

The invention is illustratively exemplified in the accompanying drawings in which—

Fig. 1 is a plan view, and

Fig. 2 is an end view of a part of a wood-mat or frame work made according to the present invention.

The reference character *a* indicates the bars of rectangular section each of which rests edgewise on the wire foundation *b* and is attached to the latter in the ordinary way by means of wires *c*.

Having now particularly described and ascertained the nature of my said invention and in what manner the same is to be performed, I declare that what I claim is:

A plaster mat comprising in combination, a plurality of square laths disposed parallel to each other and each having one diagonal thereof lying in a common plane which extends parallel to the surface upon which the mat is adapted to be placed, a relatively heavy supporting wire lying in a continuous plane and engaging the outermost edge of each lath whereby the wire is disposed in the tension region of the plaster held by the mat, a lighter wire extending at right angles to the first-mentioned wire on each side of each lath and closely engaging the inner faces of each lath and being out of contact with the remaining faces, the light wire being looped around the heavy wire intermediate the laths to position the laths with relation to each other.

In testimony whereof I hereunto affix my signature in the presence of two witnesses.

WERNER HEYD.
